KITE STRING TRAVERSE DEVICE

Robert W. Selleck, Rte. 4, Box 150-A, San Jose, Calif.

Filed Apr. 5, 1957, Ser. No. 651,041

3 Claims. (Cl. 244—155)

The present invention relates to a kite string traverse device adapted to convey a toy parachute or airplane from the elevation attained by a kite, and then to release the toy for a free fall to earth.

Of the prior devices employed for the attainment of this function, all of which I am aware are not commercially feasible, being composed of several elements whose assembly is difficult. Moreover, they do not easily lend themselves to their supposed employment; use by children, since operational difficulties, such as in the attachment of the device to the string, are experienced.

An object of the present invention is to provide a simplified and operably efficient kite string traverse device capable of being utilized by children without necessitating a complex assembly thereof.

A further object is to provide a kite string traverse device having a minimum number of parts, each of unitary construction and possessing great durability.

An additional object is the provision of a kite string traverse device consisting of a body and a toy release trigger, both of which can be pre-formed and thereafter quickly assembled into joined operative relationship.

It is a further object to provide a traverse device which can be mounted easily and quickly on the kite string but which will remain securely thereon during its utilization.

Another object is to provide a kite string traverse device which maintains a low frictional contact with the kite string so as to enhance its operability.

Traverse devices of the type pertinent to the present invention have most commonly been used to carry toy parachutes aloft for eventual release and are effective for this purpose since the parachute provides enough surface area to be caught and transported swiftly up the string by even a slight breeze. However, other toys, such as certain small toy airplanes, present less surface area and it is accordingly another object of this invention to facilitate the carrying of such toys through the provision of an auxiliary transport member that can be conjoined operatively with the traverse device.

These and other objects and advantages of the present invention will become apparent from the following description of the preferred embodiment shown in the accompanying drawing, in which:

Fig. 1 is a perspective view of the preferred form of traverse device operatively positioned on the string of a kite,

Fig. 2 is an enlarged vertical section taken on line 2—2 of Fig. 1,

Fig. 3 is a perspective view of the traverse device with an auxiliary transport member attached thereto,

Fig. 4 is a vertical section of the device of Fig. 3, taken on line 4—4 of Fig. 3, and

Fig. 5 is a perspective view of the transport member detached from the traverse device.

As seen in Fig. 1, the kite string traverse device, generally indicated at 10, is supported upon the string 12 attached to a conventional kite 14. The traverse device

2

10 includes an elongated body 16 which is composed of a hard-surfaced, stiffly-resilient material in the illustrated preferred embodiment thereof. As shown most clearly in Fig. 2, the body 16 has a modified, figure 8 cross-section that is formed by appropriate bending of a single sheet of thermo-plastic material. More particularly, the sheet 20 is bent to form an upper elongated tubular channel 22 which depends therefrom and is rebent to form a second elongated tubular channel 24. The sheet 10 20 thence returns to slightly lap under its beginning edge to form a normally-closed slot along the channel 22 and terminate in an arcuate, inward extension to form a third elongated tubular channel 26 positioned between the first and second tubular channels 22 and 24. The described arcuate extension substantially closes the middle channel 26 from the upper one but the middle and lower channels communicate through a narrowed opening 28.

As shown in Fig. 1, the lower tubular channels 24 and 26 receive the respective parallel legs 34, 35 of a bent wire trigger 30. The trigger 30 is in substantially U shape and has an unclosed loop 32 formed perpendicular to, and at the end of the leg 34 which projects from the channel 26. The other leg 35 of the trigger 30 is shorter than the leg 34 and extends from the base of the 25 U-shaped trigger 30 a distance substantially equal to the length of the body 16.

The trigger 30 is assembled into the body 16 by first longitudinally aligning the leg 34 with the tubular middle channel 26, and the leg 35 with the lowermost channel 30 24, and by then placing the base of the U-shaped trigger 30 against the forward edge of the body 16 immediately adjacent the narrowed opening 28 between these channels 24, 26. Such opening 28 is smaller than the diameter of the wire of the trigger 30, as can be seen in Fig. 2, 35 but the plastic sheet 20 possesses sufficient resiliency to spread apart upon application of force thereto. Hence, to assemble the kite string traverse device, the trigger 30, when aligned as described, is merely urged lengthwise into and through the body 16 until the base of the 40 U-shaped trigger 30 extends out the opposite end of such body. The sheet 20 then will return to its original disposition, narrowing the opening 28 so as to prevent the trigger 30 from accidental withdrawal. When so assembled, free sliding movement of the trigger 30 within the body 16 is limited in one direction by engagement of the base of the trigger 30 with one end of the body 16, and in the other direction by engagement of the trigger loops 32 with the other end of the body 16. As 45 can be seen in Fig. 1, this loop 32 is aligned with the upper channel 22 when assembly is complete as described.

An aperture 40 is provided in the wall 20 of the lowermost tubular channel 24 at the bottom of said channel and positioned adjacent the forward end of the body 16.

50 When the device is assembled as above described, the trigger 30 can slide from a position as shown where the leg 35 of the trigger 30 overlies the aperture 40 to one where it is withdrawn therefrom.

The body 16 of the traverse device, having the resiliency hereinbefore mentioned, is quickly mounted on the kite string 12 by spreading the sheet 20 at its lapping juncture point (Fig. 1 and 2) so as to admit the string 12 within the uppermost tubular channel 22. The unclosed loop 32 likewise is guided over the string 12. It 55 will be noted that the string need not be broken to enable the mounting nor need it be threaded endwise through the channel 22 or loop 32.

A toy parachute to be conveyed up the kite string by the traverse device 10 is attached, as by means of a looped string or a perforated support tab to the leg 35 of the trigger 30 by positioning said looped string or 60 perforated tab within the aperture and then sliding the

trigger 30 until the leg 35 projects through such loop or tab. The trigger 30 thus functions as a releasable keeper for holding the parachute to be conveyed.

The parachute to be conveyed is released from the hand after securing it to the traverse device 10 as just described, whereupon the wind will carry the toy and the entire traverse device 10 therewith upwardly along the kite string 12. Upon reaching the string yoke usually used to attach a kite string to a kite, or an intermediate obstruction such as a button 13 on the kite string 12, the unclosed loop 32 will be stopped from further upward movement. However, the body 16 will continue to advance with the parachute until the leading edge of said body contacts the immobilized loop 32. When this occurs, the body 16 will have moved forward relative to the trigger 30 a distance sufficient to withdraw the end of the leg 35 from the aperture 40 of the body 16 and thus automatically release the conveyed parachute for a free fall to earth.

When the traverse device 10 is separated from the parachute which carried it up the kite string 12, it will slide back down the string to the point of origin since the traverse device itself presents little surface area and gravitational force will effect such descent.

As illustrated in Figs. 3, 4, and 5, an auxiliary transport member can be employed with the traverse device 10 so that toys of lesser surface area can be carried up the kite string in the same manner as previously outlined for the transport of a toy parachute.

Such auxiliary transport member includes a support 50, formed of the same resilient thermo-plastic sheeting as the body 16, this support 50 is pre-formed to a substantially U-shaped cross-section and has a length approximately half as long as the body 16. The support 50 is formed to provide a tubular channel 52 at the base of the U and the extended legs of the U-shaped support are curved arcuately inward to intimately engage the exterior wall surrounding the lowermost channel 24 of the body 16. The arcuate legs of the support 50 are urged apart by forcing them over the body 16 and the resiliency of the thermo-plastic material of which they are formed is sufficient to secure the support 50 in a fixed position upon the body 16. Preferably, the body 16 and the support 50 are dimpled as indicated at 53 to restrain relative sliding movement thereof.

The tubular channel 52 has extending therethrough a rubber air-supply tube 54 connected at one end to a toy balloon 55 or other expandable member. The other end of the supply tube 54 still permits free passage of air since the tube is deformed only enough to secure the tab 56 by frictional engagement therewith. At its forward end, the support 50 is provided with an aperture 57, so positioned that it overlies the aperture 40 of the body 16 when the support is affixed to the body with the described dimples 53 in registry.

The free end of the tube 54 to which the tab 56 is secured is of a length such that when doubled back upon itself and positioned parallel to the body 16, an aperture 58 in said tab may receive the leg 35 of the trigger 30. When so doubled back and secured by the trigger 30, the tube 54 is bent closed at the fold as indicated at 60 and air may not pass therethrough. Thus, a simple valve means is provided and is controlled by the trigger 30 which also controls release of the toy.

To transport a toy in the same manner as described in connection with the Fig. 1 structure, the user first inflates the balloon 55 a desired amount (dependent on prevailing wind conditions, etc.). The tube 54 is then doubled back at the fold 60, and the trigger tab 56 is inserted in the aperture 40 of the body 16 together with the looped string attached to the toy. The trigger 30

is then moved so that the leg 35 enters the aperture 58 of the tab 56 as well as the looped string of the toy to secure both to the traverse device 10.

Wind then will carry the inflated balloon 55, the toy and the attached traverse device 10 aloft. Actuation of the trigger 30, as previously described, will release the toy and allow the air tube 54 to spring back to its normal straight condition when the trigger tab 56 is simultaneously released. The balloon will then deflate but remains attached to the traverse device 10 by the support 50. The assembly will then gravitate to the user.

Various modifications and/or alterations in the described structure and the manner of its fabrication can obviously be made without departing from the spirit of the invention. For example, it is apparent that the body 16 of the traverse device could be formed by an extension process rather than by bending, as described. Consequently, the foregoing description of one embodiment is to be considered as purely exemplary and not in a limiting sense; and the actual scope of the invention is indicated by the appended claims.

What is claimed is:

1. A kite string traverse device comprising a body formed into three superposed parallel channels by a single resilient sheet beginning and ending in lapping relation below the uppermost channel, and a trigger arranged within the lowermost and intermediate channels for sliding movement therein, said trigger formed in substantially a U-shape having a relatively short leg and a relatively long leg, said long leg being extended into an unclosed loop exteriorly of said body, said lowermost channel having an aperture therein adjacent one end of said short leg.
2. A kite string traverse device comprising a unitary body formed of a single sheet of material into three superposed parallel tubular channels, said sheet terminating in an arcuate extension that laps below the beginning of said sheet and forms the top of the intermediate channel positioned between the uppermost channel and the lowermost channel, said lowermost channel having an aperture therein adjacent one end of said body and a U-shaped trigger having two legs disposed for sliding movement in the intermediate and lowermost channels, one leg of said trigger protruding exteriorly of said body and having an unclosed loop formed on the end thereof, said trigger positioned for sliding movement from a position wherein the base of said U-shaped trigger abuts one end of said body and one of said legs overlies the aperture in the lowermost channel to a position wherein the unclosed loop abuts the opposite end of said body, and said one leg is withdrawn from said aperture.
3. A kite string traverse device according to claim 2, comprising a U-shaped support having arcuate legs adapted to engage the exterior of said lowermost channel and having an aperture adapted to register with the aperture in said lowermost channel; a balloon and air supply tube on said support, and a trigger tab on said tube engageable by the leg of said trigger within the apertures to hold said air supply tube in a bent, closed condition.
